nineteen per cent to Phyllis M. E. Sharp, Poca-
tello, Idaho

Application October 1, 1942, Serial No. 460,466

6 Claims. (Cl. 40—138)

This invention relates to an advertising device for use in vehicles such as street-cars, buses, etc.

One of the objects is to provide an animated sign including a fixed element and a movable element, the up-and-down vibration of the vehicle while in motion operating to drive the movable element in one direction until it reaches one limit of its movement whereupon the movement is automatically reversed and said element will travel in the opposite direction.

A further object is to provide an advertising device the fixed and movable elements of which can be caused to cooperate so as to attract the attention of passengers and also convey some message of interest to the observer and which also can be of an advertising nature if so desired.

It has been long recognized that ordinary signs used in vehicles do not attract the desired attention after once being observed because they rely solely upon printed matter to arouse the interest of the observers. The present invention is designed to intensify the interest of the observer by utilizing a movable element in connection with a fixed element so that the changing relative positions will maintain an interest.

A further object is to provide an animated sign which will operate whether or not a vehicle is moving along an inclined grade, it being due to the fact that the actuation is dependent upon bouncing or up-and-down movement of the vehicle body.

A still further object is to provide an animated sign the display portions of which can be changed readily when desired.

A still further object is to provide an animated sign which is comparatively simple in construction and will not readily get out of order, the working parts being reversible automatically when each limit of movement of the traveling element is reached.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a front elevation of the sign, a portion of the fixed display element being broken away.

Figure 2 is an enlarged front elevation with the sign support and the two display elements removed.

Figure 3 is a plan view of the structure shown in Fig. 2.

Figure 4 is a section on line 4—4, Fig. 2, said section being taken also through the support and the display elements.

Figure 5 is a detail view of the reversing mechanism in a position opposite to that shown in Figure 2.

Referring to the figures by characters of reference, 1 designates a supporting strip which can be of any desired length and is located preferably above the windows of the vehicle where the signs are to be displayed. Any desired number of signs can be mounted on this support, depending upon the length of each sign. For example one sign could be extended the full length 15 of the vehicle wall or, if preferred, two or more signs could be placed end to end, all being mounted on the support. In any case the construction of all the signs would be the same. The difference would only be in length and in matter displayed.

Each sign includes a base strip 2 mounted at suitable points on brackets 3, each bracket being provided with a clip 4 adapted to straddle the support 1 as shown in Fig. 4. Posts 5 are extended upwardly from the ends of the strip 2 and are adapted to be engaged by the stationary displaying element 6 which can be attached to the posts in any suitable manner as by means of fasteners 7.

35 A track 8 is extended longitudinally of the top surface of strip 2 and from post to post. This track can be of any construction desired. In the drawings it has been shown made up of a strip of sheet metal 9 having inturned side portions 40 10 merging into upwardly diverging flanges 11, these flanges constituting guides. Tripping pins 12 are extended upwardly from the track adjacent to the posts 5 and a guide element 13, which can be in the form of a taut wire or any other suitable device, connects the posts adjacent to those sides thereof remote from the fixed display element 6.

The movable display element, which has been indicated at 14, is adapted to be held by clips 50 15 or the like to one side of a carriage 16 which, as shown, is made up of plates 17 held apart by spacing sleeves 18 to which they are joined by screws 19 or the like. The clips 15 are provided with enlargements 20 in which are seated 55 arms 21 extending in opposite directions respec-

tively and each offset, as at 21' so as to extend across the adjacent end of the carriage and engage the guide element 13. This engaging end of the arm has a depending finger 22 for sliding engagement with one side portion of the guide element 13. Thus when the fingers of the two arms 21 are in proper position, they will hold the carriage against lateral movement relative to the guide element 13. Additional fingers 23 are connected to that side of the carriage 16 nearest the element 13 and extend downwardly across said guide element as shown particularly in Fig. 3 and Fig. 4. Thus, with the carriage properly mounted on the track as hereinafter explained, it will be held against lateral displacement and maintained in a substantially vertical position while traveling toward either of the posts.

For the purpose of supporting the carriage there are provided two downwardly diverging levers 24 and 25 pivotally mounted between the sides of the carriage near the top thereof and near the respective ends, as shown at 26. The lower portions of these levers are forked and the levers diverge downwardly, each of them having an outwardly and upwardly extended forked link 27 pivotally connected thereto as indicated at 28 and having its upper or outer end yieldingly supported by a spring strip 29 one end of which is pivotally connected to the upper end of the link as at 30 while the other end is anchored in the adjacent sleeve 18.

The pivots 28 constitute bearing pins on which are mounted toothed wheels 31 and 32 respectively, these wheels being supported on the track 8 between the guide flanges 11. Associated with each of these wheels is a double pawl, one pawl being indicated at 33 while the other is indicated at 34. Pawl 33 is pivotally mounted in the forked lever 24 and has an arm 35 extended outwardly over wheel 31 and another arm 36 extended downwardly back of said wheel. Pawl 34 is disposed oppositely to pawl 33 and is pivotally mounted in the forked lever 25, it being provided with an upper arm 37 extending outwardly from the carriage and over wheel 32 while another arm is extended downwardly back of said wheel as indicated at 38.

A spring strip 39 is anchored at its ends in the respective pawls and to the middle portion of the spring is fixedly secured an arm 40 extending upwardly therefrom. This arm is connected by a link 41 to a shifting lever 42 fulcrumed at its upper end within the carriage as indicated at 43 and extending downwardly below the carriage where it is provided with a laterally extending tripping finger 44 projecting between the pins 12. A spring 45 connects the arm 40 to the lever 42 and acts to urge said arm toward the pivot 43 whenever the arm and its link 41 are moved past a dead center.

Assuming that the parts are positioned as shown in Fig. 2, it will be noted that should a vertical vibration or bouncing action of the structure be caused by corresponding movement of the vehicle in which it is mounted, the levers 24 and 25, restrained by the inertia of the carriage 16, would be moved apart at their lower ends against the action of the spring-pressed links 27. As the spring 39, when positioned as in Fig. 2, will exert an upthrust on pawl 33 and a corresponding downthrust on pawl 34, the result of the action described will be to cause arm 38 of pawl 34 to engage and push downwardly on the adjacent toothed portion of wheel 32 while arm 35 of pawl

33 will be pulled back over the adjacent teeth of wheel 31. This action takes place during the upward movement of the supporting structure. When the rebound occurs, arm 35 of pawl 33 which has been moved backwardly or set will be thrust forwardly, thereby imparting a slight rotation to wheel 31 in the same direction as wheel 32 had already been thrust and as this action is taking place, the arm 25 of pawl 37 will be pulled back or reset relative to wheel 32. This intermittent rotation of the wheels will result in the carriage being moved longitudinally in one direction along the track and along the guide element 13. This movement will continue until the tripping finger 44 comes against the tripping pin 12 in the path thereof. When this occurs the lever 42 will be shifted from the position shown in Fig. 2 to its opposite extreme position, its lower end swinging to the right from the position shown in Fig. 2. This will cause the spring-restrained link 41 to thrust downwardly on the arm 40 and force it to the left into a position opposite to that shown so that the spring 39 will be changed to exert a thrust through arm 36 against wheel 31 and through arm 37 against the wheel 32. Consequently further bouncing action of the vehicle or other support will result in intermittent feeding of the carriage in the opposite direction or to the right in Fig. 2 until the parts are again reversed by contact of the finger 44 with the other post 12 in the path thereof. Thus the carriage will be slowly moved intermittently from one end to the other of the track, thereby causing the display element 14 to change its position relative to the display element 6. It will be of course obvious that with two display members disposed in this manner, many attractive effects can be produced and these will instantly catch the eye of the observer and maintain the interest, thereby increasing the value of the sign as an advertising medium.

It will be understood of course that tilting of the lever 42 from one position to the other moves the connection between arm 40 and link 41 past a dead center so that the spring is maintained in either extreme position to which it is adjusted, this spring 39 thus holding the pawls in their changed positions until another shift is made.

Importance is attached to the fact that the horizontal movement of this carriage and the parts carried thereby is dependent on the up-and-down vibration or bouncing of the vehicle in which the sign is located. Thus the advancing of the movable member is effected irrespective of the grade or incline of the track or street along which the vehicle is traveling.

What is claimed is:

1. The combination with a supporting structure mounted for up-and-down movement, of a carriage mounted thereon, means for guiding the carriage longitudinally of the structure, means operated by the up-and-down movement of said structure for propelling the carriage in a substantially horizontal direction along said structure, and means controlled by longitudinal movement of the carriage for reversing the direction of movement of the carriage.

2. The combination with a structure mounted for up-and-down movement due to the corresponding movement of a vehicle in which it is mounted, of a carriage, wheels mounted for movement along the structure, a yielding connection between the wheels and carriage for yieldingly supporting the carriage, and means controlled by the upward or downward movement of the struc-

ture and the inertia of the yieldingly supported body for effecting movement of the carriage in a substantially horizontal direction along said structure.

3. In an animated sign the combination with a structure mounted for up-and-down movement with a vehicle in which it is located, of a carriage including a body supporting wheels engaging the structure, and, yielding supporting means connecting the body and wheels, said means including downwardly diverging pivoted levers, and means operated by the up-and-down movement of the structure and the inertia of the carriage for effecting rotation of the wheels and movement of the carriage in a substantially horizontal direction along the structure.

4. In an animated sign the combination with a structure mounted for up-and-down movement with a vehicle in which it is located, of a carriage including a body supporting wheels engaging the structure, and yielding supporting means connecting the body and wheels, said means including downwardly diverging pivoted levers, and means operated by the up-and-down movement of the structure and the inertia of the carriage for effecting rotation of the wheels and movement of the carriage in a substantially horizontal direction along the structure, and means controlled by the longitudinal movement of the carriage for reversing the direction of movement of said carriage.

5. An animated sign for use in motor vehicles or the like including a structure mounted for up-and-down movement with the vehicle body, a carriage mounted on said structure and including a body, supporting wheels, downwardly diverging levers constituting connections between the body and wheels, yielding means for restraining the swinging movement of the levers, each of said wheels constituting a ratchet and a support, a double pawl cooperating with each of the wheels, yielding means for maintaining the pawls when in one position to rotate the wheels in one direction during relative movement of the levers and body, the inertia of the body and the up-and-down movement of the supporting structure dur-

ing the movement of the vehicle body cooperating to effect said relative movement and the actuation of the pawls thereby to drive the carriage in one direction along the supporting structure, 5 and means for automatically changing the positions of the pawls when the carriage reaches one limit of its movement, thereby to reverse the action of the pawls upon the wheels to drive the carriage in the opposite direction.

- 10 6. An animated sign for use in motor vehicles or the like including a structure mounted for up-and-down movement with the vehicle body, a carriage mounted on said structure and including a body, supporting wheels, downwardly diverging levers constituting connections between the body and wheels, yielding means for restraining the swinging movement of the levers, each of said wheels constituting a ratchet and a support, a double pawl cooperating with each of the wheels, 15 yielding means for maintaining the pawls when in one position to rotate the wheels in one direction during relative movement of the levers and body, the inertia of the body and the up-and-down movement of the supporting structure during the movement of the vehicle body cooperating to effect said relative movement and the actuation of the pawls thereby to drive the carriage in one direction along the supporting structure and means for automatically changing the 20 positions of the pawls when the carriage reaches one limit of its movement, thereby to reverse the action of the pawls upon the wheels to drive the carriage in the opposite direction, said means including a shifting lever pivotally mounted in the carriage, a spring strip connecting the pawls and anchored thereto, an arm rigidly extended from the spring strip, a link connection between the arm and the shifting lever, and cooperating means on the supporting structure and lever for 25 shifting the position of the lever when the carriage reaches a predetermined position, thereby to move the arm and link past a dead center and shift the position of the spring strip and the pawls connected thereto.
